OTHER PUBLICATIONS

Drawing of prior art lantern referred to in paragraph 3 on p. 1 of the application.

Primary Examiner—Wallace R. Burke
Assistant Examiner—Marcus Jackson

[57] CLAIM

The ornamental design for a lantern with slideable shutter, as shown and described.

DESCRIPTION

FIG. 1 is a perspective view of the lantern with slideable shutter with the shutter in the raised position;

FIG. 2 is a rear elevational view of the lantern with slideable shutter with the shutter in the raised position;

FIG. 3 is a bottom plan view of the lantern with slideable shutter;

FIG. 4 is a top plan view of the lantern with slideable shutter;

FIG. 5 is a right side elevational view of the lantern with slideable shutter, the left side elevational view being a mirror image thereof;

FIG. 6 is a front elevational view of the lantern with slideable shutter with the shutter in the lowered position; FIG. 7 is a top plan view of the lantern with slideable shutter similar to FIG. 4 with the handle in the lowered position;

FIG. 8 is a front elevational view of the lantern with slideable shutter similar to FIG. 6 with the handle in the lowered position; and,

FIG. 9 is a rear elevational view of the lantern with slideable shutter similar to FIG. 2 with the shutter in the lowered position and the handle in the lowered position.

*Fig. 1**Fig. 2**Fig. 3**Fig. 4**Fig. 5**Fig. 6**Fig. 7**Fig. 8**Fig. 9*
